UNITED STATES PATENT OFFICE.

HENRY L. TIFFANY, OF SOUTH DARTMOUTH, MASSACHUSETTS.

WINDING AND SHIPPING CONE FOR KNITTING AND LIKE MACHINES AND CAPS THEREFOR.

1,367,639.

Specification of Letters Patent.

Patented Feb. 8, 1921.

Application filed September 4, 1917. Serial No. 189,444.

To all whom it may concern:

Be it known that I, HENRY L. TIFFANY, a citizen of the United States, and a resident of South Dartmouth, in the county of Bristol and State of Massachusetts, have invented an Improvement in Winding and Shipping Cones for Knitting and like Machines and Caps Therefor, of which the following description, in connection with the accompanying drawings, is a specification, like characters on the drawings representing like parts.

This invention relates to cones particularly adapted to have wound thereon yarn, thread or the like of the commonly known cone winding form and from which yarn or thread is drawn off axially or substantially so to the needles of the knitting machine.

In order that the principle of the invention may readily be understood, I have disclosed a single embodiment thereof in the accompanying drawing, wherein;

Figure 1 is a side elevation of a winding or shipping cone embodying my invention;

Fig. 2 is a vertical sectional view of the upper part of such cone upon an enlarged scale;

Fig. 3 is a plan view of a cone having my invention applied thereto; and

Fig. 4 is a somewhat diagrammatic representation in section of a deformed tip end of a winding cone having a reinforcing member applied thereto.

Cones adapted to receive or have yarn or thread wound thereon and from which such yarn or thread is drawn off axially when in upright position to the needles of the knitting machine or for like purposes are commonly formed of paper rolled in one or more layers or coils into conical form. These cones are adapted to be mounted for winding upon tapering arbors of the general shape of the cones and extending into the same to within an inch or two of the tip end thereof. The ends of these cones protrude over the complete yarn or thread mass.

For a great many years cones were made with a square or open tip end, being of the so-called square nosed type. In the patent to Charles Gess, No. 986,379, dated March 7, 1911, is disclosed a winding and shipping cone having the apex end bent inward forming an arch accomplishing important results. The said Gess cone has gone into

very extended use and to a very large extent has supplanted the old square nosed cone.

The object of my invention is to provide means whereby a cone of the so-called Gess type, the efficiency of which has been impaired by repeated use, may be rendered perfectly serviceable for further use, and by which all the advantages of the Gess cone may be retained. To this end I preferably provide a cap-like member, which may be of relatively thin but stout paper, thin sheet metal, celluloid or the like. Preferably, however, I employ paper. The cap-like member may be molded into shape and may thereafter be applied to the desired cone, or within the scope and purpose of my invention the paper or other material in an unmolded form may be applied to the cone and formed or shaped on the cone.

In transportation and in repeated use, the inturned tip end of the cone may become somewhat damaged or deformed as by receiving a heavy blow. While the effect of such blows upon the tip end of the cone varies, and damaged cones therefore differ somewhat in shape at the tip, I have found that I may mold a paper or like cap member that can be applied to a very large proportion of such damaged cones so as to fit readily thereon and render them entirely acceptable. I will describe one form of my invention.

Referring more particularly to the drawing, the shipping and winding cone is indicated at 1, it being markedly tapering as set forth in the said Gess patent, and provided with a single superficial roughening 2. The tip end 3 of the cone is inturned as disclosed in the said Gess patent, and the opening 4 in the said tip end may be substantially or in fact entirely closed in the inturning process, since my invention is not limited in this respect.

Cones of the general character to which my invention pertains receive a large package or mass of thread or yarn wound thereon in a comparatively few number of turns or coils in each traverse of the yarn or thread from end to end of the cone. The cone must therefore be of heavy, stiff paper so as to support the large and heavy package of yarn or thread. Each wound package weighs $1\frac{1}{2}$ to 2 pounds and the wound cones are shipped in large wooden cases containing about 150 yarn packages. In transportation the tip of the Gess or round nose

cone withstands a crushing pressure far better than the square nose cone, but occasionally the tip of the round nose cone is damaged or, what is more likely, such tip 5 becomes more or less impaired in re-use. In those mills wherein winding and knitting are both carried on, it is a common practice to send the empty cone back from the knitting department to the winding de- 10 partment to be rewound, and this procedure is often carried out from five to a dozen times or more with the same cone. It is also a common practice for junk or second-hand dealers to purchase used cones from 15 knitting mills having no winding department, to sort out and classify such used cones, discarding the defective cones, if any there be, and to sell them to winding mills. Thus it comes about that the Gess or round 20 nosed cone is repeatedly used and such damage as is received by the inturned tip end is more frequently due to such continued re-use than to blows or crushing pressure in transportation.

25 In accordance with my invention, I provide for quick and cheap application to such damaged round nosed or Gess cones of a cap-like member 5 conforming to the shape of the unimpaired tip end of the cone as indicated most clearly in Fig. 2 and having a sharply inturned tip portion 6, which preferably is of just sufficient area and shape to conform to and fit snugly against the usual raw edge of the inturned tip end of the cone.

30 Such raw edge is usually of a thickness substantially corresponding to the thickness of paper or other material of which the cone is made.

The cap 5 is intended to be secured to the 40 tip end of the cone and for this purpose I preferably use some suitable adhesive such as gum. The gum or other adhesive should be applied to the entire inner surface of the cap, including the sharply inturned portion 45 6 so that such cap is tightly secured throughout its entire extent. Moreover, the material of the cap is preferably so thin as to merge, as indicated at 7, with the surface of the cone, which is preferably roughened and so 50 that no ridge is presented to the unwinding yarn or thread. Such construction is more or less diagrammatically indicated in Fig. 2. My invention is not limited in this respect, but preferably and for the best results no 55 ridge should exist at the base of the cap 5 or elsewhere. If desired, the cone 1, before the cap has been applied thereto, may be compressed or treated so as to be slightly reduced in diameter and so as in effect to form 60 an annular shoulder for the reception of the lower edge of the cap 5, thus providing for an absolutely smooth line of junction between the lower edge of the cap and the cone.

The paper or other material of which the 65 cap is or may be formed is preferably stiff

enough so that it will not enter and conform to irregularities in the tip of the cone that may exist because of some crushing action, but the cap when applied should, for the best results, preserve its rounded perfect 7 form. Preferably, however, the gum or other adhesive is applied to the entire inner surface of such cap.

A new cone is generally highly polished at the tip and this renders more difficult the application of a cap thereto or the retention of the cap in use, since the cone is apt to become battered or subjected to rough treatment in use in mills or transportation. In the case of a cone deformed in use, the tip thereof 80 presents irregular depressions or pockets which receive and retain relatively large amounts of the adhesive which is applied to the inner surface of the cap. Thus I provide localized anchors that serve most effectively 85 to retain the cap in position.

So far as I am aware, I am the first to apply to a deformed or used inturned end of a cone tip a reinforcing preferably cap-like member.

90 The cap or reinforcing member of my invention is not intended to be applied to a new or perfect winding cone having an inturned end, but to a winding cone, the inturned end whereof has become deformed or 95 impaired from any cause, as approximately indicated at 8 on Fig. 4.

Having thus described one illustrative embodiment of my invention, I desire it to be understood that although specific terms are 100 employed, they are used in a generic or descriptive sense and not for purposes of limitation, the scope of the invention being set forth in the following claims:

1. As an article of manufacture, a wind- 105 ing cone for knitting machines and the like having a roughened yarn retaining surface markedly conical in shape to permit the yarn to free itself from the roughened surface when drawn from the end of the cone and 110 having an inturned tip end deformed in use, thereby presenting irregular depressions, an applied reinforcing cap-like member upon the outer surface of the tip end and restoring the original contour thereof and adhesive material between said cap and the 115 cone and received in the said irregular depressions, thereby providing effective localized anchorings for the cap.

2. As an article of manufacture, a wind- 120 ing cone for knitting machines and the like having a roughened yarn retaining surface markedly conical in shape to permit the yarn to free itself from the roughened surface when drawn from the end of the cone 125 and having an inturned tip end deformed in use, an applied reinforcing cap-like member secured to said deformed tip end and substantially restoring the original contour thereof, and an adhesive lining the inner 130

surface of the cap and received in excess quantities in the localized deformations of the tip end of the cone.

3. As an article of manufacture, a winding cone for knitting machines and the like having a roughened yarn-retaining surface markedly conical in shape to permit the yarn to free itself from the roughened surface when drawn from the end of the cone 10 and having an inturned tip end deformed in use, thereby presenting irregular, spaced depressions, an applied reinforcing cap-like member of thin, stout paper upon the outer surface of the deformed tip and restoring 15 the original contour thereof, and adhesive material between said cap and the cone and receiving said irregular, spaced depressions, thereby providing effective localized anchorings for the cap.
- 20 4. As an article of manufacture, a winding cone for knitting machines and the like having a roughened, yarn-retaining surface markedly conical in shape to permit the yarn to free itself from the roughened surface when drawn from the end of the cone 25 and having an inturned tip end deformed in use, thereby presenting irregular, spaced depressions, said tip end having a small axial opening, the rim of which is composed of 30 the raw edge of the cone material, and an applied reinforcing cap-like member of thin, stout paper upon the outer surface of the tip and restoring the original contour thereof, said cap having an inturned rim at its 35 own tip which is co-extensive with and conforms to the said raw edge rim of the tip end of the cone, and adhesive material between said cap and the cone and received in said irregular depressions, thereby providing 40 localized anchorings for the cap.
5. As an article of manufacture, a winding cone for knitting machines and the like formed of heavy paper rolled into shape and having a markedly conical surface to permit 45 the yarn to free itself when drawn from the end of the cone in use, the conical surface being roughened throughout the greater portion of the extent thereof, the tip of the cone being inturned and originally polished and 50 smoothed, but deformed in use, thereby presenting irregular, spaced depressions, the said tip end having a small axial opening, the rim of which is composed of the raw edge of the cone material and an applied, reinforcing, cap-like member of thin, stout paper 55 upon the outer surface of the tip of the cone and restoring the original inturned contour thereof, said cap having an inturned rim at its own tip co-extensive with and conforming to the raw edge rim of the tip end of the cone, and adhesive material between said cap and the cone and received in said irregular 60 depressions, thereby providing localized anchoring for the cap, the lower edge of the 65 cap merging with the surface of the cone

without presenting a ridge, whereby a smooth, unimpaired surface is presented to the unwinding yarn.

6. That method or restoring, strengthening or renewing tips of winding cones for 70 knitting machines that have been damaged in use and which cones have a markedly conical but roughened surface permitting the yarn to free itself when drawn from the cone, consisting in providing a cap-like member 75 of thin, stout, paper-like material having a shape rendering it capable when applied to the outer surface of the tip of the damaged winding cone for restoring the original surface thereof; applying said member to the 80 tip of a winding cone originally inturned and originally polished and smooth but deformed in use, thereby presenting irregular spaced formations; and securing the said member in place by the application of adhesive material between said member and the tip of the cone and received in said irregular depressions, thereby providing localized anchorings for the said member and causing the lower edge of said member to 85 merge with the surface of the cone without presenting a ridge whereby a smooth unimpaired surface is presented to the unwinding 90 yarn.

7. That method of restoring, strengthening or renewing tips of winding cones for knitting machines that have been damaged in use and which cones have a markedly conical but roughened surface permitting the yarn to free itself when drawn from the 100 cone, consisting in providing a cap-like member of thin, stout, paper-like material having a shape rendering it capable when applied to the outer surface of the tip of the damaged winding cone for restoring the original surface thereof; said member having an inturned rim at its own tip substantially co-extensive with and adapted to conform to the raw edge rim of the tip end of the cone to be repaired; applying said member to the 110 tip of the cone originally inturned and originally polished and smoothed but deformed in use and then presenting irregular spaced depressions and with the said inturned rim applied coextensively with the original raw edge of the cone tip material; and securing the said member in place by the application of adhesive material between said member and the tip of the cone and received in said irregular depressions thereby providing localized anchorings for said member and causing the lower edge of said member to merge with the surface of the cone without presenting a ridge, whereby a smooth unimpaired surface is presented to the unwinding 115 120 125 yarn.

In testimony whereof, I have signed my name to this specification.

HENRY L. TIFFANY.
